UNITED STATES PATENT OFFICE.

CHARLES A. TURNER AND ARA B. EDWARDS, OF HAMLET, NORTH CAROLINA.

RAILWAY-SWITCH.

1,077,017.

Specification of Letters Patent.

Patented Oct. 28, 1913.

Application filed August 22, 1912. Serial No. 716,430.

To all whom it may concern:

Be it known that we, CHARLES A. TURNER and ARA B. EDWARDS, citizens of the United States, and residents of Hamlet, in the county of Richmond and State of North Carolina, have made certain new and useful Improvements in Railway-Switches, of which the following is a specification.

Our invention relates to improvements in railway switches, and it consists in the combinations, constructions and arrangements herein described and claimed.

An object of our invention is to provide means for positively locking the switch tongues, so as to prevent accidents due to the movement of the tongues away from the rails.

A further object of our invention is to provide means connected with an ordinary switch stand for operating the tongue-locking mechanism.

A further object of our invention is to provide simple and inexpensive means for accomplishing the above named results, which consist of few parts, and which are not therefore liable to easily get out of order.

Other objects and advantages will appear in the following specification and the novel features of the device will be particularly pointed out in the appended claims.

Our invention is illustrated in the accompanying drawings forming part of this application in which—

Figure 1 is a plan view of the device, Fig. 2 is an enlarged plan view of a portion of the locking apparatus, Fig. 3 is a section along the line 3—3 of Fig. 1, Fig. 4 is an enlarged section along the line 4—4 of Fig. 1, and Fig. 5 is an enlarged section along the line 5—5 of Fig. 1.

Referring now particularly to Fig. 1, we have shown therein the stationary rails 1, 2, 3 and 4, and the switch tongues 5 and 6, which are pivoted at 5^x and 6^x respectively. At 7 and 8 we have shown extensions of the cross ties, these being for the purpose of forming a base for the switch stand. The latter is mounted on a pair of cross strips or bars 9 and 10 respectively. Secured to the cross members 9 and 10 is a U-shaped frame 11 (see Fig. 3) having a plate 12 disposed on the inside thereof. A similar U-shaped frame 13 is secured to the frame 11 at one end thereof (see Figs. 1 and 3). The target rod 14 passes through the upper mem-

bers of the frames 11 and 13, being held in position by means of a collar 15. Upon the rod 14 is a bevel gear 16, shown in dotted lines in Fig. 3. The rod 14 passes through the lower members of the frames 11 and 13, and is provided with a crank wheel 17. A shaft 18 is rotatably carried by the frame members 11 and 12, and is provided with a gear 19 arranged to mesh with the gear 16. The opposite end of the shaft 18 is provided with a handle 19^x bearing a weight 20 at its end (see Fig. 1). Disposed above each of the extensions 7 and 8 and above the cross members 9 and 10, which, as will be seen from Fig. 4, are countersunk into the tie, is a plate 21, which bears a plurality of inverted U-shaped guide members 22 arranged to receive a slidable plate 23. The latter is provided with a cut-away portion 23^x (see Fig. 4) arranged to receive a spring-locking member 24 (see Figs. 1 and 4). A recess 25 extends upwardly from the cut-away portion 23^x into which the locking member 24 is arranged to spring to lock the plate in position. The plate 23 is provided with an inclined slot 23^a arranged to receive the bar or handle 19^x, the U-shaped guide members 22 on either side forming guide members for the bar or handle 19^x as well as for the slidable plate 23. As shown in Fig. 1 there are two of these plates 23, one disposed on each side of the switch stand.

The means for locking the switch tongues is best shown in Fig. 2. A description of one of these mechanisms will suffice, since they are both practically the same.

Referring now particularly to Figs. 2 and 5, it will be seen that we have provided on the outside of the web of the stationary rails 9 a plate 26, having a guide sleeve 27 secured thereto, and extending in the direction of the plate, as shown in Fig. 5. These sleeves are arranged to receive locking bars 28, which are provided at their ends with V-shaped recesses 29, arranged to receive one end of a bell-crank lever 30. The latter is pivoted at 31 to a bracket 32, secured to the web of the rail, and which forms in fact a laterally extending portion of the plate 26. The opposite end of the bell-crank lever 30 is attached by means of a rod 33 to one of the slidable plates 23 (see Fig. 1). The other bell-crank lever 30 on the opposite side of the track, is attached by means of a rod 34 to the other slidable plate 23. A link 35 is pivotally secured to the crank wheel 17 at

36, on one side of the rod 14. The other end is pivotally secured to a bar 37 connected with the switch tongues 5 and 6. Each of the switch tongues is provided with 5 a laterally extending lug, such as that shown at 38 in Fig. 2, arranged to extend through an opening 39 in the web of the rail. The lugs 38 form locking members and are arranged to receive the locking bars 28 when 10 the switch tongue is close to the permanent rail.

From the foregoing description of the various parts of the device the operation thereof may be readily understood.

15 Let us suppose that a train is approaching along the track from a direction indicated by the top of Fig. 1, and that the engineer desires to keep on the main track *i. e.*, on the rails 2 and 4. The switch would be in 20 the position indicated in Fig. 1 in which it will be seen that the switch tongue 5 is locked to the rail 1, while the switch tongue 6 is away from the rail 4. If now the engineer desires to take the siding he presses 25 down on the spring locking member 24, with his foot, thereby bringing the locking member out of the recess 25. He now raises upwardly on the weighted handle 19^x. The latter engages the upper edge of the slot 23^a 30 (see Fig. 4), thereby forcing the slidable plate 23 toward the rails, *i. e.*, in the direction indicated by the arrow in Fig. 1. This will cause a movement of the bell-crank lever 30 into the dotted line position shown in 35 Fig. 2, thereby withdrawing the locking bar 28 from the locking lug 38 of the switch tongue 5. Further rotation of the handle 19^x will cause a movement of the rod 37 in the direction indicated by the arrow in 40 Fig. 1, thereby bringing the switch tongue 6 close to the rail 4 and withdrawing the switch tongue 5 from the rail 1. Still further rotation of the handle 19^x will bring it to the companion sliding member 23 on the 45 opposite side of the switch stand, the slot of this sliding member being in the position indicated by Fig. 4. It will be seen that as the handle is forced downwardly into the inclined slot the slidable plate will be moved 50 away from the rails, *i. e.*, in the direction indicated by the arrow in Fig. 4. This will cause a movement of the bell-crank lever 30 on the opposite side of the rail in the direction of the curved arrow, and its locking 55 bar 28 will now pass through the opening in the locking lug 38, so as to lock the switch tongue 6 to the rail 4. At each throw of the operating handle 19^x from one side to the other, it will be apparent that the first 60 action is the unlocking of the locked switch tongue, then a movement of the switch tongues to their proper position, and the subsequent locking of the other switch tongue in its shifted position.

65 We desire to call attention to the fact

that if any obstruction, such as snow or ice should prevent a movement of the switch tongue close against the rail, the handle 19^x cannot be forced into the inclined slot 23^a 70 in the slidable plate 23, because it is necessary for the switch tongue to be close to the rail in order for the locking bar 28 to enter the opening in the locking lug 38, otherwise the bar 28 will strike against the lug 38, thereby preventing further movement of the 75 bar, and also preventing further movement of the slidable plate 23. The very fact that the operator cannot force the handle down into the slot 23^a will show him at once that something is wrong. The obstruction can 80 be removed, and the switch tongue may be locked. The construction described above will prevent the derailing of the train even if the bar 37 which controls the movements of the switch tongues should be broken. Ordinarily there would be nothing to keep the switch tongues from moving away from the rails if such were the case, but in our invention the tongue which is next to the rail is 85 positively locked to the rails so that no matter whether the bar 37 is broken or not the tongue will remain in its position until manually unlocked. It will also be observed that no more effort is required to operate the switch and the switch locking mechanism than in the ordinary switch, since the locking of the switch is accomplished by the movement which turns the target. The attachments which permit of the locking of the switch tongues are simple in construction and are not liable to easily get out of order. 90

We claim:—

1. The combination with stationary track rails and movable switch tongues for each 105 rail, of an operating handle, means connected with said operating handle for simultaneously shifting said switch tongues, means operated by the handle for locking either of said switch tongues, said means comprising a slidable plate arranged to be moved by 110 said handle, a lug carried by said switch tongue and arranged to project through said track rail, a slidable bar carried by said track rail and arranged to pass through said 115 lug, and means connected with said slidable plate for operating said slidable bar.

2. The combination with stationary track rails and movable switch tongues for each 120 rail, of an operating handle, means connected with said operating handle for simultaneously shifting said switch tongues, means operated by the handle for locking either of said switch tongues, said means comprising a slidable plate arranged to be moved by 125 said handle, a lug carried by said switch tongue and arranged to project through said track rail, a slidable bar carried by said track rail and arranged to pass through said lug, and a bell-crank lever pivotally mounted 130

on the outside of the rail, one end of said bell-crank lever being arranged to engage said slideable bar and the other end being pivotally connected to said slideable plate.

5 3. The combination with stationary track rails and movable switch tongues therefor, of an operating handle, means connected with said handle for shifting said switch tongues, a slideable plate disposed on each 10 side of said switch stand, means connected with one slideable plate and arranged to be operated by a movement of said handle for locking one of said switch tongues, and means connected with the other slideable 15 plate and arranged to be operated by a movement of said handle for locking the other of said switch tongues.

4. The combination with stationary track rails and movable switch tongues therefor, 20 of an operating handle, means connected with said handle for shifting said switch tongues, a slideable plate disposed on each side of said switch stand, each of said slideable plates being provided with a slot having 25 inclined edges arranged to be engaged by a movement of said operating handle for shifting said plates, a downward movement of said handle serving to shift the plate in one direction, and an upward movement

serving to shift it in the opposite direction, 30 and means connected with each slideable plate for locking one of said rails when the plate is shifted in one direction, and for unlocking it when it is shifted in the other.

5. The combination with stationary track 35 rails and movable switch tongues therefor, of an operating handle, means connected with said handle for shifting said switch tongues, a slideable plate disposed on each side of said switch stand, each of said slideable plates being provided with a slot having 40 inclined edges arranged to be engaged by a movement of said operating handle for shifting said plates, a downward movement of said handle serving to shift the plate in 45 one direction, and an upward movement serving to shift it in the opposite direction, means connected with each slideable plate for locking one of said rails when the plate is shifted in one direction, and for unlocking 50 it when it is shifted in the other, and spring means for locking one of said slideable plates.
